The ornamental design for a tray for reagent holders, as shown and described.

DESCRIPTION

FIG. 1 is a top-front-left perspective view of a tray for reagent holders, showing my design;

FIG. 2 is a top-rear-right perspective view thereof;

FIG. 3 is a top-rear perspective view thereof;

FIG. 4 is a top-front perspective view thereof;

FIG. 5 is a top plan view thereof;

FIG. 6 is a bottom plan view thereof;

FIG. 7 is a right side elevational view thereof, the left side elevational view being a mirror image of the right side elevational view; and,

FIG. 8 is a top-front-left perspective view thereof with a plurality of reagent holders.

The broken lines shown in FIG. 6 depict portions of the tray for reagent holders that form no part of the claimed design. The broken lines shown in FIG. 8 depict environmental subject matter and form no part of the claimed design.
